CLAIM

The ornamental design for portable stands for laptop computer, as shown and described.

DESCRIPTION

FIG. 1 is a first isometric view of a first embodiment of the new design;

FIG. 2 is a second isometric view of a first embodiment of the new design;

FIG. 3 is a top view of a first embodiment of the new design;

FIG. 4 is a side view of a first embodiment of the new design;

FIG. 5 is a third isometric view showing the first embodiment half folded;

FIG. 6 is a fourth isometric view showing the first embodiment folded;

FIG. 7 is a first isometric view of a second embodiment of the new design;

FIG. 8 is a top view thereof;

FIG. 9 is a side view thereof;

FIG. 10 is a front view of the half folded second embodiment;

FIG. 11 is a rear view of the half folded second embodiment; and,

FIG. 12 is a second isometric view showing the second embodiment folded.
